ANVIL FOR A UNIVERSAL-JOINT REMOVING TOOL

Robert L. Sly, 2855 Evergreen Ave., Salt Lake City, Utah

Original design application July 25, 1960, Ser. No. 61,513.
Divided and this application May 8, 1961, Ser. No.
65,112

Term of patent 14 years

(Cl. D54—13)

FIG. 1

FIG. 2

FIG. 4

FIG. 3

FIG. 5

FIG. 1 is a top plan view of an anvil for a universal-joint removing tool embodying my new design;

FIG. 2 is a side elevation thereof as seen from the right of FIG. 1;

FIG. 3 is a side elevation thereof as seen from the left of FIG. 1;

FIG. 4, a front elevation thereof;

FIG. 5 is a bottom plan view thereof; and

FIG. 6, a rear elevation thereof.

This application is a division of my copending application Serial No. D. 61,513 filed July 25, 1960, now Patent Number D. 193,580.

I claim:

The ornamental design for an anvil for a universal-joint removing tool, substantially as shown and described.
